UNITED STATES PATENT OFFICE.

BERT R. WRIGHT, OF POUGHKEEPSIE, NEW YORK, ASSIGNOR TO THE DE LAVAL SEPARATOR COMPANY, OF NEW YORK, N. Y., A CORPORATION OF NEW JERSEY.

MEANS FOR EXCLUDING DIRT AND LIQUID FROM BEARINGS AND DRIVING MECHANISM OF CENTRIFUGAL MACHINES.

1,386,148.

Specification of Letters Patent.

Patented Aug. 2, 1921.

Application filed February 7, 1920. Serial No. 357,104.

To all whom it may concern:

Be it known that I, BERT R. WRIGHT, a citizen of the United States, residing at Poughkeepsie, county of Dutchess, and State 5 of New York, have invented a new and useful Improvement in Means for Excluding Dirt and Liquid from Bearings and Driving Mechanism of Centrifugal Machines, of which the following is a full, 10 clear, and exact description, reference being had to the accompanying drawings, which form a part of this specification.

My invention relates to centrifugalizing machines having vertical spindles. The object of my invention is to prevent the entrance of dust, water, milk or other foreign substances to the top bearing or the interior 15 of the casing containing the driving mechanism and at the same time prevent the waste 20 of oil; and to accomplish these results without the addition of parts that would create additional friction.

It is well known that when the centrifugalizing bowl is removed from a centrifugal cream separator or any other machine 25 of like construction, dust is apt to settle on the top bearing around the spindle and there is great danger that it will eventually work into the bearing and cause rapid wear. 30 There is also great danger that, when the bowl casing is being washed, water will fall onto the bearing or the spindle and pass downward between the bearing and the spindle into the frame, where it will mingle with 35 the oil and cause rapid deterioration of the machine.

Many attempts have been made to prevent this entrance of dirt and water. Devices which are fairly efficient for the prevention 40 of entrance of dust are known, but these devices cannot be relied on to keep out water which falls onto and follows down the bowl spindle.

In the accompanying drawings, which 45 illustrate a preferred embodiment of my invention:

Figure 1 shows a cross section of a part of a machine equipped with my invention.

Fig. 2 shows to a larger scale the details 50 of my invention.

The frame *f* is shaped and bored, as usual, to provide for the reception of the cylindrical top bearing *c* and the extension there-

through of the spindle *b* supporting the bowl *a*. The bearing is so shaped as to hold 55 between it and the bore or hub of the frame a bearing or cushion spring *d*. A tubular shell *e*, of a diameter adapted to fit tightly within and against the bore or hub in the frame, is directly engaged by the spring *d*. 60

Through the frame *f*, below said hub or bore, a top screw *g* projects above a collar *h* on the spindle *b* and prevents the spindle being drawn out of the frame.

The shell *e* is turned outward so as to 65 overlie the hub of the frame and thence upward at *i* to a height considerably above the top of the bearing.

A dust cap *j* rests on top of the upturned edge *i* of the shell *e* and has a petticoat *k* 70 depending outside of the shell and another petticoat *l* depending inside the upturned edge of the shell *e* to a level below that of the top of the bearing *c*. Around the central hole this dust cap is turned upward 75 and outward, forming a neck *m* and an outwardly extending top flange *n*.

Fitting closely around the spindle *b* is a sleeve *o* having an outwardly turned flange *p* at the bottom and the wide umbrella-like 80 flange *q* at the top. The length of the member *o* is such that, when the flange *p* rests on top of the bearing, the umbrella *q* clears the top of the flange *n*. The inside diameter 85 of the neck *m* is of such size that the maximum oscillation of the spindle will not cause the member *o* to strike the neck.

It is obvious that any dust falling into the machine toward the bearing will be 90 caught by the umbrella *q* or the cap *j* and so kept from the bearing. Large quantities of water falling on the umbrella *q* or dust cap *j* will flow off and down into the depressed space in the frame *f* around the bearing supporting the hub. I have, however, found 95 that water falling one drop at a time acts differently. Tests have been made with a device which, except for the omission of the flange *n*, is the same as the specific construction herein described. It was observed that

100 frequently a drop of water running over the edge of the umbrella *q* would be held between it and the dust cap *j* by capillary attraction. A second, a third and more drops would add themselves to the first until 105 the space between the umbrella and the

dust cap was filled and water would pass over the neck *m* and thence down onto the bearing. The space between the top of the bearing and the under side of the bowl was

5 too small to permit of sufficient slope to prevent this. I have found that the flange *n* does effectually prevent it.

10 The outside petticoat *h* depends so far that capillary attraction cannot cause water to pass upward inside of it and over the edge *i*.

15 The rapidly rotating spindle, assisted by the flange *p*, throws drops of oil outward. These strike the inside depending petticoat *l* and fall to the bottom of the bearing case.

20 When in operation the member *o* soon takes such a position on the spindle that it will barely clear the top of the bearing and so runs without friction.

25 20 From the above description it will be seen that without adding to the friction of the machine my device will effectually exclude dirt and liquids from the top bearing and the interior of the frame and prevent the escape of oil.

Having now fully described my invention, what I claim and desire to protect by Letters Patent is:

30 1. In a centrifugal machine, the combination with an upright spindle and its bearing, of a frame surrounding the bearing; a shell comprising a lower cylindrical portion confined between the frame and the bearing and an upper portion bent outward from the 35 upper end of the cylindrical portion and thence upward; and a separate dust cap comprising a part resting upon the upturned edge of the shell and a petticoat depending from such part and extending outside and spaced from the upturned end of the shell.

40 2. In a centrifugal machine, the combination with a spindle and its bearing, of a frame surrounding the bearing, a shell between the frame and the bearing bent outward and upward; and a dust cap comprising a part overlying the shell, a petticoat depending within the shell and a petticoat depending outside the shell.

50 3. In a centrifugal machine, the combination with a spindle and its bearing, of a sleeve fitted on the spindle, an annular hood on the sleeve to deflect dirt and water, and a dust cap surrounding the sleeve and spindle and having a central aperture under and 55 protected by said hood and adapted to receive on its outside surface dirt and water deflected by said hood and guide the same away from said bearing.

60 4. In a centrifugal machine, the combination with a spindle and its bearing and a supporting frame surrounding the bearing, of a member surrounding and fitting the spindle above the bearing, means on said member adapted to catch dust and receive 65 and outwardly deflect water, a shell between

the bearing and the supporting frame and having an upwardly extending flange, and a petticoat adapted to carry water so deflected away from said shell.

5 In a centrifugal machine, the combination with a spindle and its bearing and a casing surrounding the bearing and having an upturned edge, of a contrivance to prevent access of fluid and solid foreign matter to the bearing comprising a member surrounding and fitting the spindle, means outside said member and above said casing adapted to catch dust and receive and outwardly deflect water, and a petticoat depending from said means and surrounding the upper part of said casing and adapted to carry water so deflected outside the bearing.

6 In a centrifugal machine, the combination with a spindle and its bearing and a frame surrounding the bearing, of a member surrounding and fitting the spindle above the bearing, means outside said member adapted to catch dust and receive and outwardly deflect water, a petticoat adapted to carry water so deflected away from said bearing, and an oil catcher and deflector arranged outside said spindle fitting member, beneath said dust catching and water deflecting means and inside said petticoat.

7 In a centrifugal machine, the combination with a spindle and its bearing and a casing surrounding the bearing and having an upturned edge, of a member surrounding and fitting the spindle, means outside said member and above the casing adapted to catch dust and receive and outwardly deflect water, a petticoat depending from said means and surrounding the upper part of said shell and adapted to carry water so deflected outside the bearing, and a member inside the upturned edge of the casing adapted to catch and deflect oil.

8 In a centrifugal machine, the combination with a spindle and its bearing and a frame surrounding the bearing, of a member surrounding and fitting the spindle, a flange at the bottom of said member above the bearing, means outside said member adapted to catch dirt and receive and outwardly deflect water, a petticoat adapted to carry water so deflected away from said bearing, and a member arranged beneath said dust catching member and water deflecting means and inside said petticoat and adapted to catch oil thrown outward beneath said flange.

9 In a centrifugal machine, the combination with a spindle and its bearing, of a frame surrounding the bearing, a shell between the bearing and the frame and bent outward and upward, a centrally apertured dust cap overlying and surrounding the top of the shell and having a central neck spaced from the spindle and flanged outward at

its top, and a member fitted to the spindle and overlying the flanged neck of the dust cap.

10. In a centrifugal machine, in combination, a spindle, a bearing therefor, a bearing inclosing shell having an upstanding edge higher than the top of the bearing; a dust cap comprising a part overlying the shell, two petticoats, one outside and the other inside said upstanding edge, a central upstanding neck and a flange extending from the central neck; and a spindle fitting member above the bearing having at the bottom an annular flange and at the top 15 an umbrella-like flange extending outwardly beyond the flanged neck of the dust cap.

11. A dust guard comprising a sheet metal ferrule arranged to frictionally engage the spindle of a centrifugal machine, an annular flange on one end of the ferrule adapted to form a dust and water shed, and a sheet metal shell having a cylindrical opening of smaller diameter than the flange on the ferrule, said shell having an annular flange 25 arranged to frictionally engage the wall of the bearing opening in the frame of the machine.

12. A dust guard for a centrifugal machine comprising a sheet metal flanged ferrule arranged to frictionally engage the spindle of a centrifugal machine, and a sheet metal shell for incasing the bearing and having an annular flange for frictionally engaging the bearing support in the frame 35 of the machine, and a sheet metal member on said shell having an opening for the spindle and ferrule.

13. In a centrifugal machine, the combination with a spindle, a surrounding bearing

support, an intermediate bearing having a 40 part overlying the bearing support, and a spring element between the bearing and the surrounding bearing support, of a sleeve surrounding the spindle having at its lower end a flange overlying the bearing and at 45 its upper end a flange operating to catch dust and deflect water, and a petticoat adapted to carry water so deflected away from the bearing.

14. In a centrifugal machine, the combination with a spindle, a surrounding bearing support, an intermediate bearing having a 50 part overlying the bearing support, and a spring element between the bearing and the surrounding bearing support, of a sleeve 55 surrounding the spindle having at its lower end a flange overlying the bearing and at its upper end a flange operating to catch dust and deflect water, and an oil catcher and deflector arranged outside and spaced 60 from said sleeve.

15. In a centrifugal machine, the combination with a spindle, a surrounding bearing support, an intermediate bearing a part 65 overlying the bearing support, and a spring element between the bearing and the surrounding bearing support, of a sleeve surrounding the spindle having at its lower end a flange overlying the bearing and at its upper end a flange operating to catch dust 70 and deflect water, and a second dust guard and water deflector extending under and substantially beyond the last named flange and spaced from said sleeve.

In testimony of which invention I have 75 hereunto set my hand at Poughkeepsie on this 30 day of January, 1920.

BERT R. WRIGHT.
